US00D995289S

(12) **United States Design Patent** (10) **Patent No.:** **US D995,289 S**
Putnam (45) **Date of Patent:** **** Aug. 15, 2023**

(54) **CONTAINER**(71) Applicant: **Kraft Foods Group Brands LLC**,
Chicago, IL (US)(72) Inventor: **Michael D. Putnam**, Chicago, IL (US)(73) Assignee: **Kraft Foods Group Bands LLC**,
Chicago, IL (US)(***) Term: **15 Years**(21) Appl. No.: **29/831,353**(22) Filed: **Mar. 18, 2022****Related U.S. Application Data**

(62) Division of application No. 29/658,520, filed on Jul. 31, 2018, now Pat. No. Des. 948,331.

(51) **LOC (14) Cl.** ..... **09-03**(52) **U.S. Cl.**USPC ..... **D9/425**(58) **Field of Classification Search**USPC D7/400, 601, 608; D9/416, 417, 420,
D9/425-429, 430, 432, 761CPC . B65D 1/26; B65D 1/40; B65D 5/243; B65D
81/3453; B65D 2581/34; B65D
2581/3404; B65D 2581/3456

OTHER PUBLICATIONS

Bonner, Charles D., Dough packaging with icing containment,
abandoned U.S. Appl. No. 11/246,370, filed Oct. 7, 2005.

(Continued)

Primary Examiner — Janice Patyk(74) *Attorney, Agent, or Firm* — Fitch, Even, Tabin &
Flannery LLP(57) **CLAIM**The ornamental design for a container, as shown and
described.**DESCRIPTION**FIG. 1 is a perspective view of a container, showing my new
design.

FIG. 2 is a top plan view thereof.

FIG. 3 is a front elevation thereof, the rear elevation being
identical.FIG. 4 is a right side elevation thereof, the left side elevation
being identical; and,

FIG. 5 is a bottom view thereof.

The broken lines in the figures illustrate the portions of the
container that form no part of the claimed design.**1 Claim, 3 Drawing Sheets**| (56)	References Cited
